CLAIM

The ornamental design for a infant support pillow, as shown and described.

DESCRIPTION

FIG. 1 is a perspective view of an infant support pillow, showing our new design; the broken lines showing the infant are for environmental purposes only and form no part of the claimed design;

FIG. 2 is a right side view thereof (relative to FIG. 1) with the infant being shown in phantom;

FIG. 3 is a left side view thereof (relative to FIG. 1); with the infant being shown in phantom;

FIG. 4 is an end elevational view at the mounted pillow end thereof;

FIG. 5 is an end elevational view of the opposite end thereof;

FIG. 6 is a top plan view thereof;

FIG. 7 is a bottom plan view thereof;

FIG. 8 is a perspective view of an infant support pillow, showing a second embodiment of our new design;

FIG. 9 is a right side view of FIG. 8 (relative to FIG. 8) with the infant being shown in phantom;

FIG. 10 is an end elevational view at the mounted pillow end of FIG. 8;

FIG. 11 is an end elevational view of the opposite end of FIG. 8;

FIG. 12 is a top plan view of FIG. 8;

FIG. 13 is a bottom plan view of FIG. 8;

FIG. 14 is a view similar to FIG. 8, but showing the second pillow reversed relative to its orientation of FIG. 8.

FIG. 15 is a right side view of FIG. 14 with the infant being shown in phantom;

FIG. 16 is an end elevational view of the mounted pillow end of FIG. 14;

FIG. 17 is an end elevational view of the opposite end of FIG. 14;

FIG. 18 is a top plan view of FIG. 14; and,

FIG. 19 is a bottom plan view of FIG. 14.
